UNITED STATES PATENT OFFICE.

DAVID J. BROUGHER, OF HARRISBURG, PENNSYLVANIA.

SKINNING-KNIFE ATTACHMENT.

SPECIFICATION forming part of Letters Patent No. 369,314, dated September 6, 1887.

Application filed June 28, 1887. Serial No. 242,813. (Model.)

To all whom it may concern:

Be it known that I, DAVID J. BROUGHER, a citizen of the United States, residing at Harrisburg, in the county of Dauphin and State 5 of Pennsylvania, have invented new and useful Skinning-Knife Attachments, of which the following is a specification.

My invention relates to butchers' knives specially adapted for skinning, to the handles 10 of which my attachments are applied or are formed as parts thereof, the special features of my improvements being a blunt parting-bit arranged to project rearward from the rear end of the knife-handle, and adapted to be thrust 15 between the flesh and the skin for disengaging the latter after the skinning has been begun with the knife, thus severing the skin by means of the parting-bit instead of with the knuckles of the clenched hand, as is now usually done, the parting-bit being preferably provided with a socket, by which it is attached to an ordinary skinning-knife handle; and my improvement also employs a guard upon the 20 front end of the knife-handle for keeping the operator's hand protected against slipping 25 from its hold on the handle while working said parting-bit.

The form and application of my device will be better understood by reference to the accompanying drawings thereof, of which—

Figure 1 is a side elevation of a butcher's skinning-knife with my parting-bit and guard attached thereto; Fig. 2, a basal view of the guard detached; Fig. 3, a cross-section of the 35 socket of the parting-bit, taken on the line $d-d'$ in Fig. 4; and Fig. 4 denotes an edge view of the parting-bit.

Similar reference-letters denote the same parts in all the views and in the further description and claims.

Letter A denotes the skinning-knife blade, the part A' being detached by a broken-away portion.

B denotes the knife-handle; G, the guard upon the same at its front end, it being a hook-formed projection adapted to stop the hand against slipping off the handle toward the knife-blade A. Said guard is secured upon the knife-

handle in any suitable manner, it being shown as provided with the socket H, adapted to 50 embrace the wood sections of the handle, and formed with the slot I', through which the blade A is admitted to bring the socket to its seat on the handle, on which it is secured by the rivet H', as shown. The parting-bit D is 55 also formed with the socket C, into which the handle B is fitted, and secured therein by the screw a. I, however, do not limit the construction to a parting-bit attached by a socket thereon to a knife-handle, as other means for 60 attaching the bit to said handle may be substituted, for the parting-bit may be formed as a part of the handle or of the knife-shank. I, however, prefer to form the parting-bit and 65 socket as one piece and to attach it to an ordinary skinning-knife handle, as shown. The parting-bit D is located or directed to be nearly in the plane of the side of the knife-handle, as shown in Fig. 4.

The inclined part D' is so formed that it shall 70 serve to thrust the skin aside from the flesh while the parting-bit D is thrust down in the act of severing the skin from the flesh.

The knife-blade A is ground beveled to bring the edge to a side thereof to lessen the 75 liability to cut the skin.

I claim—

1. In combination with the handle of a skinning-knife, the parting-bit D, formed with blunt edge and arranged on the side of the handle B, as and for the purpose set forth.

2. In combination with a butcher's skinning-knife, the parting-bit D, formed with the inclined shoulder D' and the socket C, and secured upon the knife-handle B, sub- 85 stantially as and for the purpose set forth.

3. The combination, with a butcher's skinning-knife, of a parting-bit, D, attached to the rear end of the knife-handle, and the guard G, attached to the front end of said handle, sub- 90 stantially as and for the purposes set forth.

DAVID J. BROUGHER.
